UNITED STATES PATENT OFFICE.

WILLIAM A. BOCK, OF CHICAGO, ILLINOIS.

CAR-MOVER.

1,354,277.

Specification of Letters Patent. Patented Sept. 28, 1920.

Application filed September 19, 1919. Serial No. 324,827.

To all whom it may concern:

Be it known that I, WILLIAM A. BOCK, a citizen of the United States, residing at Chicago, in the county of Cook and State 5 of Illinois, have invented a certain new and useful Improvement in Car-Movers, of which the following is a full, clear, concise, and exact description, reference being had to the accompanying drawings, forming a 10 part of this specification.

This invention relates to improvements in car movers.

One object of the invention is to provide a device for moving cars along the tracks 15 as for instance in freight yards and on sidings, which device comprises few parts relatively inexpensive to manufacture and easy of operation.

Another object of the invention is to provide a car mover which will be adjustable to various sizes of rails.

A still further object of the invention is to provide a car mover of the character above indicated which will in no wise injure or mutilate either the rails or car 25 wheels against which it is placed during the operation of moving the car.

In the drawing forming a part of this specification, Figure 1 is a broken elevational view of a portion of a car wheel, a portion of a rail, and my improved car mover shown in position ready to move the car. Fig. 2 is a top plan view of the car mover shown in place on a rail. Fig. 3 is 35 a vertical, sectional view taken substantially on the line 3—3 of Fig. 2 and illustrating details of construction of the car mover. And Fig. 4 is a detailed sectional view taken substantially on the line 4—4 of Fig. 40 1 and illustrating details of construction.

In said drawing, the rail is indicated by the letter A, the same having a tread of usual form designated by the numeral 10. A portion of one of the wheels of a car 45 is indicated by the numeral 11.

The improved car mover as shown, consists broadly of an operating lever designated generally by the letter B, a clamp designated generally by the letter C and 50 a wheel engaging shoe designated generally by the letter D.

The clamp C consists of two preferably like parts designated C'—C', the same be-

ing loosely mounted on a pin 12 passing through suitable perforations in the top parts of the clamp elements C'. The pin 12 is headed at each end as indicated at 13 so as to hold the parts in assembled relation. Each of the clamp elements C' is provided with a perforation 14 to accommodate the pin 12, the perforations 14 being slightly larger than the pin 12 so as to permit a certain amount of swinging movement of the clamping elements C' with respect to the pin 12. The opposed adjacent faces of the clamping elements C' at the tops thereof in proximity to the pin 12 are somewhat beveled, as indicated at 15 so as to permit the relative swinging movement hereinbefore mentioned. At the bottoms, the clamping elements C' are provided with depending flanges or fingers 16—16 adapted to engage the side edges of the tread 10 of the rail, the clamping elements C' being formed as indicated at 17—17 to also fit on the top of the tread 10. Each clamping element C' is also cut away below the pin 12 as indicated at 18 to permit relative movement therebetween as will be understood. The lever B may be 20 made of any suitable form, preferably as a forging, and has a widened or enlarged section intermediate its ends as indicated at 19. This widened section contains a centrally disposed elongated opening 20 of 25 sufficient width to loosely accommodate the clamp C therein. The upper and lower walls of the opening 20 are curved as indicated at 21 to facilitate relative swinging movements between the lever B and the 30 clamp C. The lower wall 21 also supports the clamp in a substantially vertical position when the device is being shifted along the track. The side walls of the opening 20 are also flared downwardly so as to co-operate with the correspondingly inclined surfaces 20^A of the clamp elements C' when the latter are wedged tight against the rail. 35

On the upper face of the enlarged section 19 of the lever B, bearing surfaces 40 22—22 are provided for the rounded headed ends 13 of the pin 12 so that said pin and the clamp carried thereby may move back and forth relatively to the lever B. The latter is provided however with upstanding 45 shoulders 23 to limit the movement of the

clamp and pin 12 toward the lower end of the lever B, as clearly indicated by Figs. 1 and 3.

At its lower end, that is the end adjacent to the wheel, the lever B is forked as indicated at 24 and between the arms of the fork is received a depending flange 25 of the shoe D. On the upper faces of the arms of the fork rounded bearings are provided as indicated at 26 to accommodate corresponding curved pivot lugs 27, formed integrally with the shoe D on opposite sides of the flange 25 so that, as will be evident, the shoe D is adapted for pivotal movement with respect to the lower end of the lever B. The extreme end of the lever B is beveled or chamfered as indicated at 28 to permit the pivotal movements of the shoe D, it being understood that the latter is of a width at its top corresponding substantially to the width of the lever B at its lower end. The bearing surface 29 of the shoe D is curved to conform to the curvature of the rims of car wheels now in service. To prevent accidental separation of the shoe D and the lever B, any suitable means may be employed such as the pin 30 which passes through an arcuate slot 31 in the flange 25 and has its ends seated in the forked end of the lever B.

To obtain the necessary leverage in operating the lever B, the latter may have an extended integral arm, but preferably I employ a handle as indicated at 32 which is slipped over a tang 33 formed on the lever B. Said handle 32 may well be a hollow pipe or a wooden stock.

The operation is as follows. The operator applies the clamp C in its loose condition to the tread 10 of the rail adjacent to the wheel of the car to be moved and with the shoe D in engagement with the rim of the wheel. Pressure is then exerted on the lever B by forcing the outer end thereof downwardly and as this movement occurs, it is evident that the lever B sliding down the clamping element C will wedge the latter and thereby cause the clamp to securely grip the rail and prevent slipping thereof. The clamp thereafter acts as a fulcrum and the lower end of the lever is elevated so as to lift the shoe D which in turn causes the wheel to rotate and advance the car in a well-known manner. To advance the car another step forwardly to move the car still farther, the operator lifts the lever B which will loosen the clamping elements C so that the clamp can be shifted along the tread of the rail and the operation repeated as desired.

With my construction, as will be apparent from the foregoing description, I am enabled to obtain a grip on rails having treads of different sizes and at the same time to avoid any injury to the rail which has

heretofore been a disadvantage in connection with the use of other types of car movers commonly employed and which have necessitated using sharp teeth or projections to bite into the tread of the rail in order to obtain the necessary fulcrum in actuating the lever. My improved car mover may be manufactured at comparatively small expense, comprises few parts, is of simple construction throughout and easily operable.

70

75

Although I have herein shown and described what I now consider to be the preferred manner of carrying out the invention, the same is merely illustrative and I contemplate all changes and modifications as come within the scope of the claims appended hereto.

80

I claim:

1. In a car mover, the combination with an operating lever having an elongated slot 85 therein intermediate its ends, of a wheel engaging shoe pivotally mounted on the inner end of said lever, the opposite end of said lever being adapted for manual operation, and adjustable means for clamping a rail tread, said means comprising a pair 90 of clamping elements having flanges adapted to engage the opposite sides of a rail tread, a pin on which said elements are loosely mounted, said elements extending through said slot of the lever and adapted to be pressed toward each other when the outer end of the lever is depressed to thereby effect clamping of the rail, said clamp acting as a fulcrum for the lever in the continued movement thereof.

95

2. In a car mover, the combination with an operating lever having an elongated slot 100 therein intermediate its ends, of a pair of oppositely facing clamping elements extending through said slot, the latter being longer than the dimension of said elements taken lengthwise of the lever where said elements pass through said slot to thereby adapt the lever to swing about said elements, said elements having their lower ends formed to engage the opposite sides of a rail tread, and means for preventing said clamping elements from falling out of said slot, said elements being adapted to be pressed toward each other to clamp the rail when the lever is depressed about said clamping elements as a fulcrum.

105

3. In a car mover, the combination with an operating lever having a rectangular slot 120 therein, the four surfaces of said slot being downwardly flared, of a pair of clamping elements extending through said slot and having their outer faces beveled to cooperate with two of the flaring faces of said slot, said slot being longer than the dimension of the clamping elements lengthwise of the lever where said clamping elements pass through the slot to thereby adapt the lever to swing about said clamping elements as 125

130

a fulcrum; a pin extending loosely through the upper ends of said clamping elements, the ends of said pin extending outwardly beyond the clamping elements; and shoulders on the upper face of said lever above the slot therein with which the extended ends of said pin are adapted to engage and thereby limit movement of the clamping

elements lengthwise of the lever in one direction, the lower ends of said clamping elements being recessed to conform to the contour of a rail tread. 10

In witness that I claim the foregoing I have hereunto subscribed my name this 30th day of Aug., 1919.

WILLIAM A. BOCK.
